UNITED STATES PATENT OFFICE.

GEORGE E. DUNTON, OF NEW YORK, N. Y.

APPARATUS FOR BACKING ELECTROTYPE-PLATES.

976,856.

Specification of Letters Patent. Patented Nov. 29, 1910.

Application filed September 23, 1907. Serial No. 394,152.

To all whom it may concern:

Be it known that I, George E. Dunton, residing at New York city, county of New York, State of New York, a citizen of the United States, have invented certain new and useful Improvements in Apparatus for Backing Electrotype-Plates; and I do declare the following to be a full, clear, and exact description of the invention, such as will enable others skilled in the art to which it pertains to make and use the same.

My invention relates to improvements in apparatus for backing electrotype plates, and more especially to backing them under pressure.

One of the most important objects of my invention is to furnish a direct communication between the melting pot and the backing pan and cause the molten metal to flow from the melting pot to the backing pan or receptacle containing the shell, and controlling the flow of said metal, and thereby allowing the molten metal from the melting pot to flow and be pumped directly from the melting pot into the said pan or receptacle and onto and over the shell therein. Heretofore the molten metal has been dipped out of the melting pot, by means of a ladle, and poured over the shell in the pan.

Another object is to provide means for forcing the molten metal from the melting pot into the pan or receptacle containing the shell.

A still further object is to provide a device which is simple, inexpensive and durable in construction and easy to operate.

The invention consists in the several features and combination of features as herein-after more specifically described, and claimed.

Referring to the drawings—Figure 1 is a central longitudinal section. Fig. 2 is a similar view, showing a modified form of construction.

In the drawings 1, indicates the furnace, 2 the melting pot provided with a flange 3, which seats on a lip 4 of the furnace. A pump 5, having a cylinder 6, is seated and secured on a bracket 7, at one side of the furnace, and is provided with an inlet pipe 8, one end inserted and secured in the side of the melting pot and the other end in the side of the pump cylinder, through which the molten metal flows from the melting pot into the pump cylinder, 9 being an outlet pipe, one end inserted in and secured to

the pump cylinder and the opposite end restricted somewhat to form a nipple or nozzle and inserted and seated in a hole 9^a, in the backing pan and passing through an aperture 10 in the wall of the furnace. The pump is provided with a piston 11 having its lower portion cut off at an angle as at 12, a piston rod 13, and a handle 14, pivoted to a bracket 15 extending from the upper edge of the melting pot, said handle being provided with an elongated slot 16 to receive a pin 16^a which connects the piston rod and handle. A suitable backing stand 17, is provided, having leveling screws 18 and lock nuts 19 therefor.

The backing pan 20 is seated on and leveled by means of the screws 18, and its cover or closure 21, which in this instance is shown as the platen of a press 22, is provided with a vent 23 and plug 24, for closing said vent operated by a handle 25.

26 is the hand wheel of the press secured to the upper end of a clamping screw 27, which is carried by the pivoted yoke 28. It will be seen that by the use of the pivoted yoke the clamping screw, hand wheel and yoke can be swung out of the way when not in use.

The platen 21, is preferably placed on and removed from the backing pan and inserted into the molten metal in the furnace by means of a block and tackle 29, having a hook 30, which engages with links 31, pivoted to the top of the platen. A blast pipe 32 is provided through which air is forced by means of a suitable blower, not shown, for the purpose of cooling the backing pan.

In the modification shown in Fig. 2, the pump is shown as placed within the melting pot or kettle and submerged in or under the molten metal instead of outside the melting pot as shown in Fig. 1.

Referring to the modification, 1^a, indicates the melting pot, 2^a, the furnace, 3^a the backing stand, 4^a the backing pan supported on screws 5^a, and provided with a cover or closure 6^a, which in this instance is the platen of the press, 7^a, which is provided with a pivoted yoke 8^a having a clamping screw 9^a and hand wheel 10^a. The pump in this case is provided with a cylinder 11^a secured in the bottom of and inside the melting pot and has an inlet 12^a leading from the melting pot into said cylinder, and outlet pipe 13^a leading from the cylinder into the backing pan. 14^a is the piston of the pump which

is provided with a piston rod 15^a and a handle 16^a for operating said piston.

The operation is as follows:—The electro-type shell is produced in the usual manner by being prepared and treated as for ordinary backing, and is placed in the backing pan. This pan containing the prepared shell is swung into the melting pot and allowed to float on the molten metal therein until the solder melts, when enough metal is poured over to cover the shell, the edges are then rubbed or pressed down to seal the shell to the pan, preventing any metal from being forced under the shell when pressure is applied. The pan containing the covered shell is then swung out of the melting pot, by means of a block and tackle or other means, and deposited on the four leveling screws provided for it on the backing stand beside the furnace. With the pan in position on the leveling screws and the nipple entering the recess in the rim of the backing pan the cover or closure of the pan is swung into the kettle or pot by the same device we used for the pan and allowed to come to the same temperature as the said pan containing the prepared shell. While this platen, cover or closure is heating I allow the metal to flow directly into the pan onto and over the shell covering the shell and rising to the top of the rims of the pan by lifting or raising the pump handle. This handle raises the piston above the inlet connecting the pump cylinder with the inside of the melting pot or kettle and as long as this piston is above the inlet the metal runs or flows directly from the pot or kettle through the inlet into the pump cylinder or chamber, then through the outlet pipe into the backing pan.

The platen, cover or closure having become heated to the temperature of the metal in the pot or kettle is lifted out of the pot or kettle and swung into place with its under side resting on the rims of the pan thus forming a closed box. It is secured by a hand wheel, screw, or by clamps or other suitable means. The pan having been filled with metal as shown, a vent placed in one side of the platen, cover or closure, is closed by a plug manipulated by a lever. The pump plunger is then forced down into the cylinder or chamber, which closes the inlet into the pump and forces what metal there is in the chamber under the piston into the pan. In this manner an extra amount of pressure is brought against the shell forcing every part of its surface against the pan. A blast of air is now directed against the under side of the pan cooling the cast. When it is set or cooled sufficiently to handle it is removed from the closure or pan and cleaned and finished in the usual manner.

The construction, shape and position of

the backing pan and its cover or closure may be changed as desired. The box or pan may be made curved or semi-circular. Although I impart pressure to a stream of molten metal being transmitted to a backing pan or other receptacle, which is preferably closed by a cover or other means, yet an open backing pan or receptacle may be used, that is to say, without a cover or closure. I also may use a box or pan having a cover or removable side but open at the end.

I do not desire to be understood as limiting myself to the specific details as herein described as it is manifest that variations may be made without departing from the spirit and scope of my invention and improvements, I therefore reserve the right to all such variations and modifications as properly fall within the scope of my invention and the terms of the following claims.

What I claim is:—

1. In an apparatus for backing electro-type plates, a furnace, a melting pot, a backing pan, a cylinder having an inlet substantially parallel with the bottom of the melting pot, and an outlet substantially parallel with the inlet and below the bottom of said melting pot, a pipe connecting the outlet of the said cylinder with the backing pan, the outer end of said pipe being below the bottom of said melting pot and a piston in said cylinder for cutting off the flow of metal into and forcing it out of the cylinder, substantially as described.

2. In an apparatus for backing electro-type plates, a furnace, a melting pot, a backing pan, a cylinder having an inlet substantially parallel with the bottom of the melting pot and an outlet below the bottom of said melting pot, said outlet being substantially parallel with the inlet, a pipe connecting the outlet of said cylinder with the backing pan and being substantially parallel with the upper portion of the backing pan, the outer end of said pipe being below the bottom of said melting pot and a piston in said cylinder for cutting off the flow of metal into and forcing it out of said cylinder, substantially as described.

3. In an apparatus for backing electro-type plates, a melting pot, a cylinder having an inlet pipe connected to and substantially parallel with the melting pot, an outlet pipe below the outlet end of the inlet pipe and a piston in said cylinder for cutting off the flow of metal into and forcing it out of said cylinder, substantially as described.

In testimony whereof I affix my signature in the presence of two witnesses.

GEORGE E. DUNTON.
